UNITED STATES PATENT OFFICE

FRANK L. SIMS, OF SEATTLE, WASHINGTON, ASSIGNOR OF ONE-FOURTH TO LOUIS HAVEN, OF SEATTLE, WASHINGTON

VALVE FOR INTERNAL COMBUSTION ENGINES

Application filed April 21, 1931. Serial No. 531,770.

The present invention relates to improvements in valves for internal combustion engines, and has for an object to provide an improved cooperating valve stem and washer which will dispense with the necessity of making openings through the valve stems which weakens the valve stem and causes same to break.

Another object of the invention is to provide an improved cooperating valve stem and washer in which the washer is provided with lugs and the valve stem with cooperating grooves, whereby there is a cooperating locking engagement directly between these two elements without necessitating the use of any further parts, such as keys and the like.

A further object of the invention is to provide an improved construction of valve and washer which will eliminate labor and make it extremely easy to disengage and remove the valves.

With the foregoing and other objects in view, the invention will be more fully described hereinafter and will be more particularly pointed out in the claims appended hereto.

In the drawing, wherein like symbols refer to like or corresponding parts throughout the several views,

30 Figure 1 is a side elevation of the valve in closed position with the valve seat shown in section.

Figure 2 is a perspective view of the valve detached.

35 Figure 3 is a perspective view of the improved washer.

Figure 4 is a central vertical section through the washer.

40 Figure 5 is a fragmentary side elevation of a modified form of valve stem on an enlarged scale, and

Figure 6 is a similar view of a further modified form.

45 Referring more particularly to the drawing 10 designates generally the cylinder block and 11 the opening therein through which the valve stem 12 projects. The valve head or valve body is indicated at 13, and such valve is adapted, in the usual manner, to close against 50 the valve seat 14 of the block 10.

In accordance with the usual practice, a coil spring 15 is employed to surround the valve stem 12 and to abut at one end against the cylinder block 10, and at its other end against a washer 16, which is usually affixed 55 to the valve stem as by the use of valve keys or other separate parts.

In accordance with the present invention, this washer 16 is provided with a pair or more of lugs 17, projecting into the central 60 opening 18 of the washer; and these lugs are adapted to cooperate with grooves made in the valve stem 12. These grooves comprise entrance grooves 19, which entrance grooves extend substantially parallel with the axis of 65 the valve stem 12 and open through the lower end of such valve stem. These entrance grooves 19 progress a suitable distance and then communicate at their inner portions with circumferential or lateral grooves 20, 70 which in turn communicate with locking grooves 21, which locking grooves extend downwardly from the transverse or circumferential grooves 20, and terminate at their lower ends in closed sockets in which the 75 projections or lugs 17 of the washer 16 are adapted to rest in interlocking engagement.

Now the washer 16 is constructed in accordance with the conventional manner by providing a concavity 22 on one side and a 80 convex surface 23 on its opposed side. On the convex side, the washer is modified from the usual plan, by the formation thereon of an annular seat or groove 24, extending within an outer marginal ridge 25.

85 Referring more particularly to Figure 5, a modified form of the valve stem 12a is shown having an elongated entrance groove 19a, which communicates with a series of lateral or circumferential grooves 20a and 20b leading from the entrance groove 19a in opposite directions and stepped at different elevations. Each of the lateral grooves 20a and 20b terminates in or communicates with a closed locking groove 21a or 21b. As many of these 90 lateral and locking grooves may be provided, as desired, upon one or both sides of the central entrance groove 19a.

95 Referring more particularly to Figure 6, a further modified form of the invention is 100

shown, in that the valve stem 12c is provided with an entrance groove 19c communicating with a lateral groove 20c and with a locking groove 21c. From off the lateral groove 20c extends a further entrance groove 19d communicating with a further lateral groove 20d and its locking groove 21d. In like manner, other and further entrance, lateral and locking grooves may be provided in any suitable number and in any suitable relation and arrangement.

In the use of the device, the spring 15 is put in place over the stem 12 after the valve has been inserted through the block, and the upper end of the spring 15 is fitted against the block while the lower end is engaged with the washer 16. This washer is simply forced upwardly with its lugs 17 entering the entrance grooves 19, the spring 15 being compressed before it. As soon as the lugs 17 reach the lateral grooves 20, the washer is rotated so as to turn the lugs 17 over into registry with the locking grooves 21. Thereupon, the washer is released and the expansive action of the coil spring 15 will force the washer downwardly so that the lugs 17 will seat in the closed sockets of the locking grooves 21. In this position of the parts, there will be an effectual locking engagement between the washer and the valve stem, which engagement will be impracticable to disturb during any normal running operation of the engine; moreover, it will be apparent that all separate parts, such as locking keys and the like heretofore used for securing the washer upon the valve stem, are eliminated. Likewise, the necessity for making new openings through the valve stems and thus weakening the same is dispensed with.

It will be further noted that such added parts, as are now found necessary, usually drop to the bottom of the crank case and are difficult to recover. Usually, the pan must be dropped afterwards and the oil drained so as to reclaim all such parts which would do great injury to the motor were they left in the crank case.

Moreover, it will be noted that the release and removal of the valve is greatly facilitated by the use of the present invention, inasmuch as the washer may simply be pushed upwardly toward the cylinder block and then rotated to free the lugs, and the coil spring 15 will then eject the lugs 17 through the entrance grooves 19, thus automatically freeing the washer; or the valve 13 itself may be rotated to effect this disengagement when the lugs 17 are brought into alignment with the transverse grooves 20.

Now the washer 16 is preferably countersunk along both edges of its central opening 18 to cooperate with the bevelled or reduced edge 26 of the valve stem 12. This arrangement will facilitate the entry of the stem 12 through the opening in the washer 18, ir-

respective of which side of the washer is presented to the valve stem. Ordinarily, the concave side 22 of the washer will be presented to the spring 15, the concavity forming a natural seat for the end convolutions of the spring 15. However, when the spring is to be subjected to a greater amount of tension, this result may be secured by simply reversing the washer 16 so that its convex side 23 will be presented against the end helices of spring 15, which helices will in that event rest in the seat 24 and be confined and retained in place by the annular ridge 25 of such washer. In this way the spreading of the lower portion of the spring 15, which spreading might be fostered by the convex portion 23 of the washer, is avoided owing to the fact that the terminal convolution of the spring has a depressed seat 24 in the washer and is confined circumferentially by the ridge 25.

When the washer 16 is lifted, that is, pressed upwardly toward the cylinder block, it will automatically raise the valve 13 easily from its valve seat and will thus do away with the necessity of cranking the motor to extract the valve, which procedure is that ordinarily resorted to by mechanics to get the valves out of the motor.

It will be obvious that various changes in the construction, combination and arrangement of parts could be made, which could be used without departing from the spirit of this invention, and I do not mean to limit the invention to such details, except as particularly pointed out in the claims.

Having thus described my invention, what I claim and desire to secure by Letters Patent of the United States is:

1. An improved valve for internal combustion and other motors, including a valve stem having a locking groove, a coil spring surrounding said stem, and a reversible concavo-convex washer having means for interlocking in either position with said groove and for confining the end of the spring in place.

2. An improved valve for internal combustion and other motors, including a valve stem, a coil spring extending about said valve stem, a washer having a central opening with countersunk portions at both sides thereof for quick entry upon the valve stem, said washer having a convex face and an opposed concave face, said convex side of the washer having a seat with a raised ridge thereabout for retaining the spring end.
